GUS JORDAHL, OF PALM BEACH, FLORIDA

SEA-SHELL WHISTLE

Application filed March 26, 1930. Serial No. 439,120.

This invention relates to improvements in whistles, and the object is to first exercise the faculty of selection in finding a sea-shell appropriate for the purpose, secondly slotting it at such a place that when the breath is blown in at the slot a whistling sound will be emitted.

Reference is made to the accompanying drawing in which,

10 Figure 1 is an elevation of the improved sea-shell whistle.

Figure 2 is a cross section taken on the line 2—2 of Figure 1.

As has been indicated already, the purpose 15 of the invention is to convert a sea-shell into a whistle by which conversion an object otherwise useless for any purpose other than possibly ornamentation is converted into an instrument of utility.

20 The particular sea-shell generally designated 1 is of the species *Nevita Pelevonta*, otherwise commonly known in localities where it is found as the "bleeding-tooth" shell. This species of shell is found in abundance along the sea coast of Florida and southwest as far as the West Indies.

Its general characteristics are that of a hollow body 2 which has a single D-shaped opening 3 the curved part of which is defined by the rounded back or extension 4 of the body 2, the erect or straight part of which is defined by a lip 5 that represents the other terminal of the body.

25 This lip is dished in as seen in Figure 2 thus defining a resonance chamber 6 that is well adapted to a whistle. It is in the external surface of the lip 5 that pronounced tinges of red appear thus suggesting the name quoted above.

30 Teeth 7 appear on the edge of the lip 5. The number of these teeth varies. Sometimes shells will be found with only one distinct tooth. More often shells are found with two distinct teeth, and even shells with 45 a suggestion of three teeth can be found.

Cut into the rounded back 4 is a slot 8. This can be filed in or produced in any other appropriate manner. When filed it will partake of the same general D-shape of the opening 3 (Fig. 1) by virtue of the rounded contour

of the back. The slot or opening 8 is to be blown into, for which purpose the adjoining part of the back 4 becomes the mouthpiece.

It is important to so locate the opening 8 that the breath will be blown directly across the orifice 9 of the chamber 6 in the direction of the arrow 10. The air thus blown across carries with it some of the air of the chamber 6, creating a partial vacuum there and setting up the rarefaction half of a sound-wave. 60 This is reflected from the inside of the chamber and is followed by the condensation half of the wave from the outer air.

The effect is a rapid vibration of the air column in the chamber 6 and a resultant 65 whistle sound. It is here that the teeth 7 play an important part. Rather than producing a mere lifeless sound the teeth have the effect of "voicing" the whistle so that a tone of some quality is emitted. By placing the whistle in his cupped hand so that the body 2 rests in the palm with the opening 3 turned outwardly the user will blow into the opening 8 which he should leave exposed between the thumb and forefinger, 70 whereupon the other part of the hand acts as a bell-mouth which tends to reinforce the sound.

It is important to locate the opening 8 properly. A line drawn across the orifice 80 9 from the substantial center of the opening should clear the lower bulge 11 of the body 2 as indicated by the extension 12 of the arrow 10. A shell so converted will make the shrillest and best whistle. If the opening 8 be located either higher up or farther down upon the rounded back 8 the whistle becomes far more difficult to blow. In the instance of lowering the position of the opening toward the edge of the extension 4 the 85 air blast will be divided by the lip 5 so that the required vibration in the chamber 6 will be interrupted.

In addition to this mechanical aspect the whistle also involves the method of its production. It is not possible to use all sea-shells for the purpose, hence the first step is a factor of selection of a species which possesses a hollow body having a lip opposing its rounded back. The next step is to prop- 100

erly locate the opening 8 so that the film of air blown across the orifice 9 will set the air column to vibrating and, in fact, itself act somewhat on the order of a vibrating reed.

5 I claim:—

1. A whistle consisting of a sea-shell of the species *Nevita Pelevonta* which comprises a hollow body having a bulge and a rounded back extending to an edge line which substantially meets the bulge and having a lip extending from the bulge in spaced but confronting relationship to the back to define an orifice for the hollow body, said rounded back having an opening substantially in line with the lip and the bulge.
- 10 2. A whistle comprising a shell having a hollow body with a rounded back and an opening, a lip extending inwardly from the opening to define an orifice, said back being perforated with a hole in alignment with the lip and the side of the opening from which the lip extends.
